ELECTRICAL APPARATUS

Theodore J. Smulski, Gary, Ind., assignor to The
Anderson Company, Gary, Ind., a corporation
of Indiana

Application April 19, 1930, Serial No. 445,648

3 Claims. (Cl. 177—351)

My invention relates to electrical apparatus and particularly relates to electrical apparatus adapted to commensurably reproduce at a given point as a force or movement, forces or movements, existing at another point which may be disposed relatively remotely to the said first point.

Although my invention in its broader phases is susceptible of application to a wide variety of uses, it has a particular use to the indication of thermal effects, movements of an element, pressure effects or the like at a point distant therefrom, and without requiring the transmission of motion directly between the two points.

15 In my prior applications, Serial No. 133,426, filed September 3, 1926, Patent No. 1,885,050, granted October 25, 1932, and Patent No. 1,885,051, granted October 25, 1932, I disclosed apparatus of the general type operable in electrical systems for the above general purposes, 20 and therein disclosed electro-thermal responsive actuating means for the controlling and controlled elements of the system consisting of bimetallic strips of metal with a heating element therefor to be operated by warping from its original, preferably straight form, to a more 25 arcuate form to perform the mechanical functions required of the said mechanisms.

Such bimetallic strips provided the quality 30 of heat storage to any desired predetermined degree, except that I have found that considerable care is required in the preparation of such strips and their installation in the mechanism to accurately predetermine the quantitative heat 35 retentivity of such strips and their associated heating elements. Also, I have found that care must be taken to prevent changes gradually occurring in the responsiveness of the bimetallic sheet metal strips employed, after the devices have been put into use.

40 In another application previously filed by me, Serial No. 169,114, a wire under tensile stress is provided with an electrical heating element, which communicating heat to the wire, elongates it and tensile stress being simultaneously resiliently applied to the wire, its resultant elongation, when heated, effects operation of suitable apparatus provided.

It is found that this mechanism is difficult 50 to adjust and that the heat storage effects are also difficult of predetermination for quantity production of the instruments.

Also the extensible wire employed must necessarily be of small gauge and the heat storage effects therefor must be obtained otherwise by 55

the mass of metal contained in the extensible wire with resulting difficulties in manufacture in quantities.

In my present invention, I employ, preferably for the actuating element of the controlling 5 and/or controlled mechanisms, a plain metal rod of steel, brass or other preferably metallic material, though my invention is not limited to the use of metallic rods, which are electrically heated to effect elongation of the rods, the relative movement of the ends of the rod, due to elongation, thermally effected, being employed to actuate the elements of the mechanisms sought to be electro-thermally actuated.

Such rods operate the actuatable part of the 15 mechanisms with considerable force, so that the mechanisms may be made more sturdy than heretofore. The thermal storage qualities of such rods may be very accurately predetermined, since these rods are preferably turned 20 to a given diametrical dimension and length at a given temperature and thereafter retain their original mass and therefore thermal properties.

From the above and by reference to the accompanying specification of a preferred embodiment of my invention, the following objects of my invention will be understood:

It is an object of my invention to provide an improved thermally operable mechanism for the effecting at a remote point, a movement or force 30 commensurable with an original movement and/or force at another point.

Another object of my invention is to provide an improved sturdy controlling mechanism for an electrical system of the type described.

Another object of my invention is to provide an improved relatively sturdy controlled mechanism for a system of the described type.

Another object of my invention is to provide controlling and/or controlled mechanisms for 40 systems of the described types when employed for any useful purpose.

Another object of my invention is to provide for controlling and/or controlled mechanisms of the general type herein described, an improved 45 primary actuating means susceptible to ready, accurate and inexpensive production in quantities, all produced elements having like predetermined thermal characteristics.

Another object of my invention is to provide an 50 improved actuating element for mechanisms of the described type with which a thermal element may be intimately associated in such a manner as to effectually communicate heat thereto, and without undesirable loss of heat from the heating ele- 55

ment by radiation, or air currents, had without heating the said actuating element.

Another object of my invention is to provide mechanisms of the described type which are readily susceptible to adjustment after being assembled, and which being once adjusted will operate in a predetermined manner for long periods of actual use.

Other objects of my invention, and the invention itself will become apparent by reference to the accompanying drawing of an embodiment controlling and an embodiment controlled element of my invention included within a typical system, wherein the said mechanisms may be advantageously employed.

Referring to the drawing:—

Fig. 1 is a longitudinal medial sectional view of a controlling mechanism embodying the principles of my invention;

Fig. 2 is a top plan view of the mechanism of Fig. 1 with the cover cap removed, and not shown;

Fig. 2a is a plan view of one of a pair of contact springs shown in Fig. 2;

Fig. 2b is a plan view of another of the said pair of contact springs;

Fig. 2c is a plan view of an adjustment element for the controlling mechanism;

Fig. 3 is a side elevational view of the mechanism of Fig. 1;

Fig. 4 is a top plan view of the mechanism of Fig. 3;

Fig. 5 is a section taken on the line 5—5 of Fig. 2;

Fig. 6 is a plan view of an indicator mechanism embodying the principles of my invention;

Fig. 7 is a section taken on the line 7—7 of Fig. 6;

Fig. 8 is a section taken on the line 8—8 of Fig. 7;

Fig. 9 is a diametric view of the controlling and indicator mechanisms of the foregoing figures in a typical electrical system.

Referring now first to the controlling mechanism of Figs. 1 to 5 inclusive, the embodiment of my invention illustrated therein is in the form of a controller adapted to electrically relay to an indicator such as that shown in Figs. 6—8 inclusive, a mechanical effect which is commensurable to the temperature which may exist, for instance, in the water cooling jacket of an internal combustion engine, upon the outer wall 1 of which the controlling mechanism of Fig. 1 is mounted, as shown in Fig. 1.

The controller of Figs. 1 and 3 comprises a tubular support 2 supporting a plate 3 at its one end, a neck of the support being projected through an aperture of the plate and then headed over as shown at 4 to rigidly secure the two parts together as an integral structure.

A casing 5 is then mounted on the plate 3 and comprises a base 6 of insulating material and an inverted metal cap 7 adapted to be fitted by its rim 8 over the peripheral edges of the plate 3, which is in the form of a disk. The tubular support 2 is provided with a reduced exteriorly threaded end 9, whereby the support may be screwthreaded into a wall 1 of a water containing casing which, as illustrated in Fig. 1, may be a water cooling jacket of an internal combustion engine. Secured within the bore of the support 2, coaxial therewith, and projecting from an end thereof, I provide a tube 10 which makes intimate engagement with the inner walls of an inwardly extending annular flange 11 of the support at its fixed end, and which is preferably slightly spaced

in other portions towards its free end from the interior walls of the support bore. The fixed end of the tube 10 is preferably secured as by soldering to the tubular walls of the support 2, in a leak proof manner, so that water from the jacket may not penetrate to the interior of the tube 10.

The tube 10 carries at its end a metal plug 11 through which a pivot screw 12 is axially screw-threaded to a proper adjusted position, whereupon the end of the plug 11 is soldered over at 13 to prevent water from penetrating along the screw threads of the screw 12 to the interior of the tube 10.

Within the casing 5 an electrical contact mechanism is provided, comprising an electrical contact element 14 and an opposing cooperative contact element 15, supported on metallic leaf springs 16 and 17, respectively. The leaf springs 16 and 17 extend forwardly from their secured ends 20 and 25, each of which is twice perforated at 24', 24", 25' and 25", whereby the leaf springs may be securely mounted on a mounting plate 21. The springs 16 and 17 are rigidly secured to the bottom wall 6 of the casing 5, by screws 24 extending therethrough and through suitable strips 22 and 23 of electrical insulating material, interposed between the leaf springs and between the leaf spring 16 and the plate 21, all of which are thereby relatively electrically insulated from each other; insulating bushings 38 electrically insulate the screws 24 from the spring 16 and said plates. The leaf spring 17, however, by its secured portion 26 through the screws 24 makes electrical connection with the metal parts of the casing and support, and through the support 2 and the jacket wall 1.

Ordinarily the internal combustion engine having such a jacket wall is electrically connected to a grounded pole of the battery. Where the engine is an automobile engine, the battery is preferably that usually provided for the purposes of ignition, engine starting and illumination.

The springs 16 and 17 are disposed in superposed relation at their secured and free contact carrying ends with the spring 17 outermost. The intermediate portion of the spring 16, is disposed laterally from the intermediate portion of the spring 17.

The form of the contact springs is best illustrated in Figs. 2a and 2b, the contacts 14 and 15 being secured to their free ends and their fixed ends being perforated as shown at 24' for the admission of the screws 24, above mentioned. The spring 16 is provided with a projecting portion 26 which is perforated to receive an electrical circuit conductor 19 leading from a heating element 27 to be described; the spring 17 is provided with a centrally disposed bearing recess 28, on its inner side adapted to receive the pointed end of an actuator rod 29, about which the preferably silk insulated electrical circuit conductor forming the electrical heating resistance element 27 is wrapped, preferably non-inductively, as shown within the tube 10. The other pointed end of the rod 29 is received within a similar bearing of the end face of the screw 12 which by adjustment is advanced sufficiently to establish proper operative contact between the two ends of the rod and the bearing recess of the screw 12 and spring 17, respectively.

The insulated resistance wire 27 after being wrapped on the rod is preferably painted with a heat hardening material to retain it in place.

The tube 10 is, preferably, made of metal 75

which has a greater co-efficient of thermal expansion than does the metal from which the rod 29 is made, and when, for instance, the tube 10 is of brass and the rod 29 of iron or of a chrome-nickel alloy material, when the water shown at 5 31 disposed between the jacket walls 1 and 1', possesses a certain temperature such as 150°. The length of the tube, due to thermal expansion thereof, will be so increased as to retract the 10 rod 29 sufficiently to effect closure of the contacts 14 and 15, and previously assumed to be separated, because of engagement between the rod and the spring 17 to deflect said spring. Closure of the contacts 14 and 15 will complete an electrical circuit comprising a source of current in 15 the manner diagrammatically indicated in Fig. 9 to effect a current flow through the heating element 27 for the rod 29.

An electrical terminal connector consisting of 20 a screw 34 projecting outwardly through the plate 21 and a clamping nut 36 provides a means for holding the casing cap 7 onto the insulating plate 6 and also for effecting an electrical connection to an end of the heating element 27 which 25 is electrically connected to the plate 21.

A tubular spacer 37 is interposed between the end wall of the cap and the outer surface of the plate 21, and, preferably, a washer is interposed between the nut 36 and the outer surface of the 30 cap. Preferably, the spacer 37 is fitted snugly onto the screw 34 so that it is retained in position thereon when the casing cap 7 is removed. The apparatus disposed within the casing 1 and including the casing 1 and insulating disk 6 are 35 rigidly secured onto the plate 3 by the screws 24 and, preferably, by an additional screw 38 screw-threaded through the insulating plate 6 and into the plate 3.

The contacts 14 and 15 may be relatively adjusted, by the provision of the relatively stiff strip 40 39 of sheet metal carrying a screw 40 at its free end screwthreaded therethrough to engage with the spring 16 to deflect its end relative to the end of the spring 17 to relatively adjust the contacts 14 45 and 15.

Referring to Fig. 9, the source of current is shown at S and current flowing through a second heating element 32 of an indicator mechanism, shown generally at 35, through circuit conductors 33, through the heating winding 27 of the controller and contacts 14 and 15 thereof to the ground pole of battery at G. Current flowing 50 through the heating winding 27 will heat the rod 29 to such an increased temperature over that of the tube 10, that it will elongate sufficiently to again exert pressure on the spring 17 to again separate the contacts 14 and 15. Subsequently, as will be more fully described, the above cycle of operations for the controller mechanism of Figs. 55 1 to 5 inclusive are periodically repeated during use of the controller mechanism.

The indicating mechanism, shown generally at 35 in Fig. 9 is specifically illustrated in Figs. 6 to 8 inclusive, wherein a casing is provided comprising a casing cup 41 and a casing cap 42 telescoped 60 by its rim 18 over the rim of the cup to closely fit the cup and cap together.

A disk 43 forming a mounting plate is disposed within the rim of the cup 41 and substantially divides the casing, comprising said cup and cap, into an actuating compartment 44 and an indicating compartment 45. A pervious dial glass 46 forms the end wall of the casing cap 42. Within the space between the end wall of the cup 70 75 41 and the disk 43, there is provided an actuating

mechanism for the indicating hand 47 having a pointer end 50, and which hand is carried by an end by a shaft 49, its pointed end 48 being journaled in a recess of the casing cup wall and projects through an aperture of the disk 43. An intermediately disposed annular flange of the shaft 49 within the compartment 44 contiguous with the disk 43 prevents such outward longitudinal movement of the shank as would remove its pointed end 48 from its bearing recess. 10

Rigidly secured on the shaft 49 in the compartment 44 I provide a lever 51 whose free end is preferably arcuate in form to make contacting engagement with a suitably formed end surface of a lever 52 which in turn is journaled on a pin 15 53 rotatably mounted in the end wall of the cup 41 and in the disk 43, respectively.

A longitudinally thermally expansible actuating rod 54 makes contacting engagement in a journaled recess 55 of a short arm 56 of the lever 52 and by its opposite pointed end is fitted within a journaled recess 57 of a longitudinally adjustable calibration screw 58, which is mounted in a lug 59 projecting into the compartment 44 from the disk 43. 20 25

A heating element 32 comprising a winding of electrical resistance wire is wound onto the rod 54. A tensile spring 61 draws the long arm of the lever 52 in such a direction as to move the short arm 56 inwardly against the end 55 of the 30 rod 54.

From the foregoing, it will be readily understood that by longitudinal adjustment of the screw 58, the rod 54 may be longitudinally displaced and by contact with the short arm 56 35 of the lever, the long arm thereof may be swung about the pivot 53 to rotate the hand 47 on its pivot shaft 49 by virtue of the engagement of the portions 52 of the lever and 62 of the element 51. All lost motion between the contacting 40 parts described is taken up by the spring 61. The electrical heating unit 32 terminates in circuit conductors 63 and 64, which are joined to connectors 65 and 66, respectively, and in turn are secured to binding posts 67 which project through 45 the end wall 41 of the casing cup, so that electrical circuit conductors 33, Fig. 9, may be electrically connected to the heating element 32 of the instrument. 50

The arrangement of the operative parts is diagrammatically illustrated in Fig. 9 wherein the thermally expansible rod 54 may be electrically heated by a winding 32 to effect expansion thereof and resultant movement of the pointer 50 for the hand 47 over the scale 68. 55

From the foregoing, it will be understood that as the length of the rod 54 is varied by varying the electrical current flowing through the heating element 32, the pointed end of the indicator hand 47 will take a position relative to the scale 60 68, whereon temperature indicia may be placed, corresponding to the thermal condition of the rod 54 under the influence of the electrical current passing through the heating element 32. 65

The operation of the entire system, the parts 65 for which have been previously described, will now be related. The parts being given the proper adjustment, as described, the tube 10 is first immersed in a fluid, the temperature of which is, 70 preferably, that of boiling water, namely 212° Fahrenheit. The electrical circuit connections meanwhile will be that shown in Fig. 9, except that during the period when adjustments are made, the switch SW may be thrown to open po- 75

sition wherein the source of current S is temporarily disconnected from the circuit.

When the tube 10 has been immersed in the boiling water 31 , so that it achieves the temperature of boiling water, the adjusting screw 12 is turned so that the contacts 14 and 15 are substantially, though but slightly broken, or are so closed that upon the merest reduction in temperature of the water 31 , they will immediately open.

The preferred adjustment is that wherein the contacts will open or close according to whether the temperature of the fluid 31 is but slightly less or slightly more, respectively, than 212° . Of course, to achieve a temperature more than 212° , a fluid different in composition from pure water must be used. This adjustment being accomplished, the recesses 13 in the plug 11 beyond the end of the screw 12 is plugged with solder or the like.

For the final adjustment the relative positions of the contacts 14 and 15 may be varied by adjustment of the screw 48 , and the adjustment provided by the screw is subsequently employed for any relative readjustment of the contacts that may be desired.

The parts of the indicator casing 41 , 42 , and 43 are, preferably, made of the same material, as is the rod 54 , or in any event is preferably made of a material whose coefficient of thermal expansion is substantially the same as that of the rod 54 . These casing parts considered as a whole are indicated by the frame element F , Fig. 9, and by making the frame F of the same material as the rod 54 , variations in ambient temperatures effecting alike the rod 54 and the frame F , will effect no rotative movement of the lever 56 , and therefore, no operative movement of the indicator hand 47 will be caused by variations merely of ambient temperatures.

The operation of the system and apparatus contained therein, arranged according to Fig. 9, will be now readily understood. Assuming that the tube 10 is immersed in a liquid of a temperature such as, for instance, boiling water at 212° , Fahrenheit, and the switch SW being closed, current will flow over the circuit conductors 33 from the source S serially through the controlling and controlled heated elements 27 and 32 and the contacts 14 — 15 , which, for instance, by adjustment of the screw 48 are closed.

The current flow through the heating elements effects an expansion both of the rods 28 and 54 with the result that the contacts 14 and 15 will soon be broken and the indicating hand 47 will have progressed along the scale 68 from left to right. Both the controlling and controlled electrically heated elements lose their heat but slowly, so that upon momentary breaking of the contacts 14 — 15 the hand 47 will recede but little until the contacts are again reclosed, due to a slight cooling of the rod 28 due to interruptions of the current flow through its energizing heating element 27 . Reclosing of the contacts will supply additional heat to the controlling and controlled expandible rods and the operation will thence continue periodically and regularly, there being pulsations of current through the heating elements with intervening non-heating periods.

Now, with the contacts periodically making

and breaking the contact the adjusting screw 48 is turned to so adjust the contact 14 that the relative length of the contact closing periods to the length of the intervening periods during which the contacts are opened is adjustably made such that the pointer 68 is positioned by the resultant expansion of the rod 54 at the scale division mark 212° .

For any lower temperature of water 31 to which the tube 10 is subsequently exposed, the hand 47 will recede towards the left, Fig. 9, and indicate the actual temperature of such water. For such lower temperatures, the controlling apparatus comprising the electrically heated rod 28 , the tube 10 and the contacts 14 — 15 , will periodically operate as before, but with the contact closure periods relatively shorter compared to the periods of contact opening.

The indications given by the pointer 68 will be alike even though the voltage of the battery S is varied, since such variation merely effects a variation in the relative periods of contact closing and contact opening, but with no variation in the heating effect produced during contact closing periods.

This fact is of great advantage where the source of current S is like the storage battery usually installed on an automobile, variable in voltage, according to whether or not it is in discharged condition, or is being charged at a high rate from an associated generator.

Having thus described my invention in a specific embodiment, I am aware that numerous and extensive departures may be made from the embodiment, system and apparatus herein illustrated and described and in the method of operating the said apparatus in systems which are other embodiments of my invention.

I claim:

1. In a thermally responsive electrical circuit controller, an expandible tube adapted to contact a fluid, an expandible rod within the tube having one end secured thereto, a set of contacts associated with the tube and adapted to be included in an electrical circuit with an indicating device, electrical heating means encircling the rod, insulated therefrom, and controlled by the contacts, the tube and rod being differentially responsive to changes of ambient temperature, one of said contacts comprising portions readily opposing extension of the rod responsive to temperature increase, the other contact being adjustable to relatively alter the relative movement of the rod and tube effecting disengagement of the contacts, and the intermittent engagement of the contacts effecting current impulses whose cumulative value in a given interval is proportional to the fluid temperature.

2. The circuit controller as described in claim 1 and wherein the tube end adapted to contact the fluid comprises a plug forming a support for the rod adjustable to effect a predetermined cumulative current value in a given interval responsive to predetermined fluid temperature.

3. The circuit controller as described in claim 1 and wherein the contacts are completely encased and the controller is adapted to be detachably secured as a unit to a wall of the fluid container.
